UNITED STATES PATENT OFFICE.

OLAF HALVORSEN AND WILLIAM T. SEIBELS, OF CHICAGO, ILLINOIS; SAID SEIBELS
ASSIGNOR TO SAID HALVORSEN.

PASS CASE.

Application filed May 29, 1924. Serial No. 716,556.

REISSUED

To all whom it may concern:

Be it known that we, OLAF HALVORSEN and WILLIAM T. SEIBELS, citizens of the United States of America, and residents of Chicago, Cook County, Illinois, have invented a certain new and useful Improvement in Pass Cases, of which the following is a specification.

This invention relates to improvements 10 in pass-cases and more particularly to foldable pocket cases especially designed for carrying passes, identification cards and the like.

The object of the invention is to provide 15 a case in which card or pass holding members are removably retained, thus permitting additional members to be added or removed at will.

A further object of the invention is to 20 provide a novel means for removably securing the card or pass holding members within the case.

The preferred embodiment of the invention 25 is disclosed in the accompanying drawings in which

Figure 1 is a perspective view of the complete case with a single card holding element secured therein;

Figure 2 is a view in elevation of the card 30 holding member and showing the manner in which the securing member is applied.

Figure 3 is a view in end elevation of the card holding member shown in Figure 2.

Figure 4 is a perspective view of the securing member,

Figure 5 is an enlarged detailed view in section taken on line 5—5 of Figure 2, and

Figure 6 is an enlarged sectional view taken on line 6—6 of Figure 1.

40 In its preferred form, the case consists of a foldable cover of soft leather, made up of an outer ply 1 and an inner ply 2, stitched together along one side and one end edge. The outer ply includes an extended end portion 3 which forms a flap for securing the case in closed position by a suitable fastener 4.

45 The cover is foldable lengthwise along a line midway between the ends, the flap 3 lapping over the ends of the case in the usual manner and fastened to the surface of the outer ply by the snap fastener 4.

50 A card holding member preferably con-

sists of two hinged-together rectangular frames 5—5, each made up of two rectangular pieces of celluloid 6, bound together at their edges by strips 7 of a suitable fabric or other binding material which is stitched around the edges of the celluloid sheets so as to leave a slot at one edge for the removal and insertion of the cords. A transverse strip 8 of the same flexible material forms the hinge between the rectangular transparent frames or card holding sections 5—5.

55 As a means for securing the card holding element to the cover or case proper, a nickled bar 9 is provided, which has pins 10—10 located near each end, said pins being bent at right angles intermediate their ends so as to form relatively short shanks 60 extending at right angles to the bar and somewhat longer portions extending parallel to and toward the opposite ends.

65 The hinged forming portion 8 of the card holding member 5 is perforated as at 11—11 and the inner cover strip 2 is similarly perforated as at 12. Thus, to remove or insert the card holding element the pins 10—10 are passed through the perforation and occupy the position shown in Figure 6. The shanks of the pins 10 are sufficiently long to 70 accommodate one or more of the card holding elements, thus the same can be added as occasion demands.

75 As clearly shown in Figure 1, a single card or picture can be inserted in each side 80 or section of the card holding member, and if desired, two cards or passes may be inserted in each section with the printed matter on each facing outwardly, so that the maximum number of cards may be inserted 85 and carried in the case.

90 The use of removable card holding members permits of expansion; a further advantage is derived, namely, that it permits their renewal whenever the same becomes 95 worn or otherwise damaged. The necessity for renewal is particularly desirable in cases of this character, for the reason that while celluloid has been found to be the only practical material to be used for the purpose, its surface becomes readily scratched and roughened within a relatively short space of time and as a result loses its transparency. Therefore, with this construction these card 100

holding elements can be readily replaced without the necessity of purchasing an entirely new case.

Having described a preferred embodiment of the invention, we claim:

1. A pass-case comprising a foldable cover of pliable material, a card holding member, consisting of frames of transparent material joined together by a section of flexible material, and a bar adapted to extend transversely of said card holding member and provided with fastening members adapted to pass through the flexible section thereof and said cover.
- 15 2. A pass-case comprising a foldable cover of pliable material, a card holding member, consisting of frames of transparent material joined together by a section of flexible material, and a bar adapted to ex-

tend transversely of said card holding member and provided with pins adapted to pass through the flexible section thereof and said cover.

3. A pass-case comprising a foldable cover, consisting of an outer and an inner 25 ply of flexible material, a card holding section consisting of flexibly connected frames of transparent material, and a bar adapted to extend transversely of said card holding section, and provided with pins adapted to be inserted through registering perforations in the flexible portion of said card holding section and the inner ply of said cover.

Signed at Chicago this 24th day of May, 1924.

OLAF HALVORSEN.
WILLIAM T. SEIBELS.
